Fig. 2.

UNITED STATES PATENT OFFICE

WILLIAM A. ROBINSON, OF SOUTH KORTRIGHT, NEW YORK.

TELEPHONE SYSTEM.

No. 803,856.

Specification of Letters Patent.

Patented Nov. 7, 1905.

Application filed February 18, 1904. Serial No. 194,259.

To all whom it may concern:

Be it known that I, WILLIAM A. ROBINSON, a citizen of the United States, residing at South Kortright, in the county of Delaware and State of New York, have invented certain new and useful Improvements in Telephone Systems; and I do hereby declare the following to be a full, clear, and exact description of the invention, such as will enable others skilled in the art to which it appertains to make and use the same.

My invention relates to certain new and useful improvements in telephone systems, and more particularly to that class of systems employed in rural districts where a number of phones are connected to one main line and wherein the return-circuit is made through the ground.

My main object, among others, is to provide a means whereby two phones may be used and the remainder of the phones upon that system locked or disconnected, so that the phones in use may not be disturbed.

A further object is to provide means whereby a phone located between the phones in use and a phone beyond said phones may converse without disturbing the phones already in use, or both phones may be located between the phones already in use.

Other objects and advantages will be hereinafter made clearly apparent, reference being had to the accompanying drawings, which are made a part of this application, and in which—

Figure 1 is a diagrammatic view of a portion of a telephone system, showing my invention applied thereto. Fig. 2 is a side elevation of the switch-controlling mechanism and interlocking device, the housing for the same being in section; and Fig. 3 is a top plan view thereof as seen from the dotted line $\alpha\alpha$ in Fig. 2.

Referring to the drawings, in which similar reference-numerals designate corresponding parts throughout the several views, 1 designates the main-line wire, and 2 the ground-wire, which are constructed in the usual and well-known way. I also employ in connection with the main line 1 a secondary line 3, to which is connected my switching and interlocking mechanism. The said interlocking mechanism consists of a main pull-rod 4 and auxiliary pull-rods 5 and 6. The rod 4 is provided at its inner end with an upward extension 7 for a purpose to be hereinafter set forth. The rod 4 is also pro-

vided near its inner end with a cross-bar 8, said bar lying in the path of the inwardly-extending ends 9 of the auxiliary rods 5 and 6, whereby when the main rod 4 is pushed inwardly the auxiliary rods will be carried in unison therewith. As best shown in Figs. 2 and 3, these parts are suitably mounted within a housing 10, the outer ends of said rods extending through the housing and provided with suitable buttons 11. Pivottally mounted within said housing and in a line with the main pull-rod 4 is a latch 12, having upon one end a cross-head 13 and provided with a notch at its opposite end, which is adapted to engage the member 7 upon the inner end of the main pull-rod 4 when desired. Immediately above the cross-head 13 I locate a magnet 14 for a purpose to be hereinafter set forth. The auxiliary pull-rods 5 and 6 are each provided with a switch-arm 15 and 16, respectively, which are in turn pivotally secured within the housing 10 and by which means the course of the current through the line 3 is controlled. The line 17, leading from the main line 1 to the phone, is provided with a switch 18, so that when desired the phone may be entirely disconnected from the main line.

In Fig. 1 of the drawings I have shown four phones, which I will designate A, B, C, and D for convenience in illustrating. Assuming that A wishes to communicate with C, the call is made on the main line 1, and C answering the same A requests him to converse over the line 3, whereupon C opens the switch 18, which disconnects his phone from the main line. He then pulls outwardly upon the pull-rod 4, which removes the same from beneath the latch 12. He then pulls outwardly upon the rod 5 until the member 9 again rests against the cross-bar 8. This action moves the free end of the switch-arm 15 from the contact-point 19 to the contact-point 20, and thus connecting his end of the line 3 with his phone and at the same time breaks the circuit between the line 3 and the battery 21 in his phone. In conjunction with C, A also disconnects his phone from the main line through the medium of the switch 18 and in the same manner pulls the rod 4 outwardly. A then pulls outwardly upon the pull-rod 6, which action moves the free end of the switch-arm 16 from the contact-point 22 and disposes the same in connection with the contact-point 23, thus completing the connection between A's phone and the line 3 and breaking the circuit between line 3 and A's battery.

21. This completes the connection between A and C over the line 3. The circuit starting from A's phone passes through that part of the line 17 between the phone and the switch 5 18 into the wire 24, which leads from the contact-point 23 to the line 17, the meeting-point of said wires being indicated by the numeral 25. The current then passes through the wire 3 to the contact-point 19 of B's phone; 10 thence through the wire 26, leading from the contact-point 19 to the magnet 14; thence through the wire 27, leading from the magnet to the battery 21; thence through the wire 28, leading from the magnet to the contact-point 22; thence again through the wire 3 to the contact-point 20 at C's phone, through 15 the wire 29, leading from the contact-point 20 to the junction-point 25 and into C's phone over the wire 17. As soon as the circuit between the line-wire 3 and the ground-wires 2 has been completed the magnets 14, interposed 20 between the phones in use, (in this instance phone B,) are magnetized and act upon the cross-head 13 of the locking-latch 12, raising 25 said cross-head and lowering the opposite end thereof until the upward extension 7 of the main pull-rod 4 has entered the notch in said latch 12, when the pull-rod 4 and auxiliary pull-rods 5 and 6 are securely locked in their 30 inward position, thus positively preventing any interruption of the line 3 from the interposed phones. It will likewise be seen that the line 3 is broken from phone A at the contact-points 20 and 22 and from phone C at 19 and 23. If, however, B desires to talk to D, they may converse over the main line 1 without disturbing A and C, as their phones are 35 cut off from the main line at the switches 18.

It will thus be seen that I have provided a 40 simple and durable device and one that can be applied to any make of phone and at any time at a minimum cost.

It will also be seen that my device will be 45 positive in its action in changing from one line to another and in preventing other persons from listening to the conversation.

While I have shown and described the preferred construction of my device, I desire to 50 comprehend in this application all substantial equivalents and substitutes as may be considered as fairly falling within the scope of my invention.

Having thus fully described my invention, what I claim as new, and desire to secure by 55 Letters Patent, is—

1. The herein-described telephone system comprising the combination with the main line and suitable phones thereon, of a secondary line and devices to break the circuit between the main line and the phones, a lever and means carried thereby to complete the circuit between any two of the phones and the secondary line and simultaneously lock

the intervening phones from connection therewith, substantially as set forth. 65

2. In a telephone system, the combination with the main line and suitable phones thereon, of a secondary line, suitable switches to make and break the circuit between the main line and the phones, a pull-rod having means 70 connected therewith adapted to complete the circuit between any two of the phones and the secondary line and at the same time lock the pull-rods of the intervening phones, whereby the intervening phones will be prevented from using the secondary line but permitting said secondary line to be used at either side of said two phones, substantially as set forth. 75

3. The herein-described telephone system, 80 comprising the combination with the main call-line having suitable phones thereon, of a secondary line, a main pull-rod having a cross-head, auxiliary pull-rods co-operating with said main pull-rods whereby the circuit 85 of said secondary line may be completed upon one side of the phone and disconnected upon the opposite side thereof, substantially as set forth.

4. In a telephone system, the combination 90 with the main line having suitable phones thereon, of a secondary line, a switching mechanism adapted to break the circuit between the main line and the phone, a pull-rod carried by each phone having auxiliary 95 rods co-operating therewith, said auxiliary rods having switch-arms pivotally connected thereto adapted to make and break the circuit between the phones and the secondary line when said pull-rods are operated, substantially as set forth. 100

5. In a telephone system, the combination with the main line having suitable phones thereon, of a secondary line and means to connect any two of said phones with the secondary line and lock the intervening phones therefrom, comprising a main pull-rod 4 having a cross-bar near its inner end, auxiliary pull-rods 5 and 6 having inwardly-extending ends adapted to extend into the path of said cross-bar, switch-arms pivotally secured to the inner ends of said rods 5 and 6 adapted to direct said secondary line from one contact-point to another, and means to automatically engage the inner end of said main pull-rod 110 whereby said main pull-rod and auxiliary rods 115 will be held against outward movement, substantially as and for the purpose set forth.

In testimony whereof I have signed my name to this specification in the presence of two subscribing witnesses. 120
